(57) **CLAIM**

The ornamental design for a docking station for tablet computer, as shown and described.

DESCRIPTION

FIG. 1 is a top, front and right side perspective view showing a first embodiment of my new design;

FIG. 2 is a top, rear and left side perspective view thereof; FIG. 3 is a bottom, front and right side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a reference perspective view of a tablet computer installed on my new design;

FIG. 11 is a top, front and right side perspective view showing a second embodiment of my new design;

FIG. 12 is a top, rear and left side perspective view thereof;

FIG. 13 is a bottom, front and right side perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof; and,

FIG. 20 is a reference perspective view of a tablet computer installed on my new design.

The broken lines are directed to environment and are for illustrative purposes only. The broken lines form no part of the claimed design.

1 Claim, 18 Drawing Sheets
